UNITED STATES PATENT OFFICE.

FREDERICK WINK, OF PHILADELPHIA, PENNSYLVANIA, ASSIGNOR TO
THOMAS DOLAN, OF SAME PLACE.

DESIGN FOR SHAWL-PATTERN.

Specification forming part of Design No. 6,078, dated August 20, 1872.

Specification describing a Design for a
Shawl - Pattern, invented by FREDERICK
WINK, of Philadelphia, Pennsylvania.

Design for a Shawl-Pattern.

The figure in the accompanying drawing
shows sufficient of a shawl-pattern to illustrate
my design, the main characteristics of which
are the two elaborately ornamented stripes A
and B. The stripe A has a central rib, *a*, or-
namented by circles or ovals arranged alter-
nately, as shown, and the said stripe is also
ornamented by plain parallel ribs of different
shades or colors, and by narrow ornamental
ribs *b* of the character represented. The stripe
B is composed of a series of parallel ribs of

varying width, its principal feature being the
central rib *d*, having the foliated ornamenta-
tion shown.

Irrespective of the colors employed, I claim—

1. The design for the stripe A, substantially
as shown and described.
2. The design for the stripe B, substantially
as described and represented.
3. The design for the whole pattern, includ-
ing the stripes A and B.

In testimony whereof I have signed my name
to this specification in the presence of two
subscribing witnesses.

Witnesses: FRED. WINK.

CLINTON M. LATOURETTE,
LEWIS T. GODFREY.
